UNITED STATES PATENT OFFICE.

JOHN H. HINMAN, OF ST. LOUIS, MISSOURI, ASSIGNOR TO HEINE BOILER COMPANY, OF ST. LOUIS, MISSOURI, A CORPORATION OF MISSOURI.

INTERNAL MANDREL FOR SECTIONAL BOILER HEADERS.

Application filed November 11, 1925. Serial No. 68,376.

This invention relates to an internal mandrel that is adapted to be arranged inside of a metal tube which is being deformed to produce a sectional boiler header or tube header of the kind described in the United States patent of Alfred Cotton for method and apparatus for making sectional headers, No. 1,565,061, dated December 8, 1925.

The main object of my invention is to produce a mandrel for the purpose described which is of such design that it can be manufactured easily by simple machine operations at a low cost.

Another object is to provide a mandrel of the type that comprises die bars and a collapsible supporting unit for the die bars, which is equipped with an efficient means for partially collapsing the die bar supporting unit at the completion of the deforming operation before the header has had a chance to seize or grip the die elements, due to cooling and shrinking of the header.

And still another object is to provide a mandrel of the type just referred to which is so constructed that after it has been partially collapsed, the mandrel and the header can be removed as a single unit from the press by exerting an upward pull on the mandrel. Other objects and desirable features of my invention will be hereinafter pointed out.

Figure 1 of the drawings is a perspective view of a Cotton boiler header.

Figure 2 is a longitudinal sectional view of a mandrel constructed in accordance with my invention, showing the mandrel expanded and arranged in operative position inside of the header.

Figure 3 is a similar view showing the mandrel partly collapsed.

Figure 4 is a longitudinal sectional view, showing the collapsible supporting means for the die bars removed, preparatory to withdrawing the die bars from the header.

Figure 5 is a horizontal sectional view, taken on the line 5—5 of Figure 2.

Figure 6 is a horizontal sectional view, taken on the line 6—6 of Figure 2; and

Figure 7 is a longitudinal sectional view, illustrating a modification of my invention.

In the drawings α designates a sectional boiler header of the kind described in the said Cotton patent, that is produced by arranging a circular or oval metal tube between two side dies and a front and rear die, and then moving said dies inwardly towards

the longitudinal axis of the tube so as to deform the tube in such a way as to produce a header having corrugated lateral sides and front and rear sides that have flat seat faces 1 disposed at an angle to the longitudinal axis of the header, which flat seat faces are adapted to have hand holes and tube holes formed in same. During the deforming operation the portions of the tube that constitute the flat seat faces 1 are internally supported by the mandrel that forms the subject-matter of this application.

Said mandrel is composed of two die bars A, each of which has a plurality of rigid die elements 2 arranged on the outer face of same, and a collapsible supporting means arranged between said die bars for holding them in rigid relation during the deforming operation, said supporting means consisting of a unit capable of being withdrawn bodily from operative position between the die bars and constructed so that it can be partially collapsed at the completion of the deforming operation, thereby permitting the die bars A to move inwardly sufficiently towards the longitudinal axis of the mandrel to prevent the die elements 2 from being gripped by the header as it shrinks.

The die bar supporting unit just referred to is preferably composed of two wedges B and B', of approximately the length of the mandrel, arranged in engagement with each other and interposed between the die bars A, as shown in Figure 2. During the deforming operation said wedges are effectively held against longitudinal movement in either direction and they are combined with the die bars in such a way that said parts co-operate with each other to produce a rigid supporting means for the portions of the tube that are being deformed to produce the flat seat face 1 of the header. In the form of my invention herein illustrated the wedges B and B' are held in fixed relation with each other and also in fixed relation with the die bars during the deforming operation, by means of a pin C that is arranged transversely through aligned holes in the upper end portions of the die bars and in the upper end portions of the wedges B and B', said pin being adapted to be inserted transversely through said parts before the mandrel is positioned inside of the tube that is to be deformed. I also prefer to equip the mandrel with a means for clamp-

ing the lower end portions of the die bars and the wedges B and B' together, the means herein illustrated for this purpose consisting of a sleeve D at the lower end of the mandrel which surrounds said die bars and wedges and provided with a guide pin 3 that enters a hole 3^a in one of the die bars, and a clamping screw 4 arranged opposite said guide pin that bears against the outside face of the other die bar, as shown in Figure 6.

Due to the fact that the wedges B and B' have a relatively slight taper, considerable force or pressure is required to displace said wedges or move one wedge longitudinally relatively to the other, so as to partially collapse the mandrel at the completion of the deforming operation. It is also necessary that the die bar supporting unit formed by the wedges B and B' be collapsed immediately after the completion of the deforming operation in order to prevent the die elements 2 from being gripped or seized by the header when it starts to cool and shrink. Accordingly, I have equipped my improved mandrel with a means that is capable of exerting sufficient pressure on one or both of the wedges B and B' in such a way as to insure partial collapsing of the mandrel, and which can be operated easily to effect this result before the header has had time to cool and shrink to such an extent that the die elements of the mandrel will be seized by the header. The means above referred to can be constructed in various ways without departing from the spirit of my invention, but I have herein illustrated it as consisting of a lever E at the upper end of the mandrel arranged so that it can be engaged and moved upwardly by the hook 5 of a hoisting apparatus and combined with the wedges B and B' in such a manner that when it is actuated or rocked upwardly it exerts pressure on at least one element of the die bar supporting unit in a direction to partially collapse said unit or cause the width of same to be reduced sufficiently to permit the die bars to move inwardly slightly towards the longitudinal axis of the mandrel. One convenient way of combining the lever E with the wedges B and B' is to pivotally connect said lever to links 6, which, in turn, are pivotally connected to the wedge B by means of trunnions or pins 7 on said wedge that project into holes in said links, the lever E being pivotally connected to the upper ends of said links by a cross pin 8 and arranged so that a curved portion 9 at the end of said lever normally bears against a curved surface 10 at the extreme upper end of the wedge B'.

During the operation of arranging the mandrel inside of the tube, preparatory to the deforming operation, the lever E and links 6 serve as a means for connecting the

mandrel to a hoisting mechanism that is used to lower the mandrel into the press. At the completion of the deforming operation the pin C at the upper end of the mandrel is withdrawn from engagement with the die bars A and wedges B and B' and the lever E is then rocked upwardly into the position shown in broken lines in Figure 2 by pressure exerted on the lever E by the hook 5 of the hoisting mechanism. During this upward movement of the lever E the curved end portion 9 of said lever rocks on the curved bearing surface 10 at the upper end of the wedge B', and the links 6 exert an upward pull on the wedge B, thereby "starting" the wedge B and causing it to break loose from the wedge B' and the die bar against which the outer face of said wedge B bears. The upward movement of the hoisting hook 5 is continued until a hole 11 in the wedge B comes into alignment with the holes in the upper end portions of the die bars and the wedge B' in which the pin C was originally positioned, and thereafter the pin C is passed transversely through said holes, as shown in Figure 3, thereby causing the wedges B and B' to be securely locked together in their displaced position and also causing said wedges to be locked with the die bars. In view of the fact that the die bars are now rigidly coupled with the die bar supporting unit of the mandrel, which, in turn, is coupled with the hoisting mechanism by means of the links 6 and lever E, the hoisting mechanism can be used to lift the mandrel and the header as a single unit out of the press, the angular shape of the die elements 2 on the mandrel and the fact that the mandrel is only partially collapsed, insuring the header moving upwardly out of the press with the mandrel. A mandrel of the construction above described can be manufactured at a low cost and by simple machine operations, owing to the fact that each of the wedges B and B' has only a single taper, consisting of a continuous, straight surface, and another desirable characteristic of such a mandrel is that it is provided at its upper end with a means, to wit, the lever E and link 6 or equivalent device, that enables the mandrel to be partially collapsed before the header has had an opportunity to shrink and grip the die elements 2 of the mandrel. Still another desirable feature of such a mandrel is that the means that is used to partially collapse the mandrel also constitutes a connection between the mandrel and a hoisting mechanism that can be used to lower the mandrel into the press and withdraw the mandrel, together with the header, from the dies of the press.

In Figure 7 of the drawings I have illustrated a mandrel that is similar to the mandrel shown in Figures 2 and 3, except that

the die bar supporting unit of the mandrel is formed by a pair of upper wedges G and G' and a pair of lower wedges F and F', said wedges being approximately one-half the length of the mandrel and arranged as shown in Figure 7.

Having thus described my invention, what I claim as new and desire to secure by Letters Patent is:

- 10 1. A mandrel for internally supporting a tube that is being deformed to produce a sectional header, consisting of die bars provided with die elements, a collapsible means for rigidly supporting said die bars during the deforming operation comprising a pair of members arranged between said die bars and provided with oppositely-inclined contacting surfaces and means for moving one of said members longitudinally of the other member at the completion of the deforming operation so as to partially collapse the mandrel and thus prevent the header from gripping the die elements.
- 15 2. A mandrel for internally supporting a tube that is being deformed to produce a sectional header, consisting of die bars provided with die elements, a collapsible means for rigidly supporting the die bars during the deforming operation comprising a pair of oppositely-inclined wedges provided with a slight taper, one of said wedges being adapted to be moved longitudinally relatively to the other wedge at the completion of the deforming operation for the purpose described, and means for enabling said wedges to be connected with the die bars so that the mandrel and header can be withdrawn as a unit from the press.
- 20 3. A mandrel for internally supporting a tube that is being deformed to produce a sectional header, consisting of die bars provided with die elements, a collapsible unit for rigidly supporting said die bars during the deforming operation comprising oppositely-movable members provided with co-operating inclined surfaces, and a means for collapsing said unit that is also adapted to be used for connecting the mandrel to a hoisting mechanism.
- 25 4. A mandrel for internally supporting a tube that is being deformed to produce a sectional header, consisting of die bars provided with die elements, a collapsible unit for rigidly supporting said die bars during the deforming operation comprising a plurality of relatively movable members, means for actuating said members to partially collapse the mandrel at the completion of the deforming operation, and means for enabling the die bars to be connected with said unit in its collapsed condition, whereby the

mandrel and the header can be withdrawn as a single unit from the press.

5. A mandrel for internally supporting a tube that is being deformed to produce a sectional header, consisting of die bars provided with die elements, a collapsible unit for rigidly supporting said die bars during the deforming operation comprising oppositely-movable members provided with co-operating inclined surfaces, and a lever combined with said members and adapted to be actuated to effect a change in the relative position of said members so as to partially collapse the mandrel.

6. A mandrel for internally supporting a tube that is being deformed to produce a sectional header, consisting of die bars provided with die elements, a collapsible unit for rigidly supporting said die bars during the deforming operation comprising members equipped with oppositely-inclined surfaces that co-operate with each other to vary the width of said unit when one of said members is moved longitudinally relatively to the other, and a lever at the upper end of the mandrel arranged to bear on one of said members and connected with the other member so as to effect relative longitudinal movement of said members when said lever is actuated.

7. A mandrel for internally supporting a tube that is being deformed to produce a sectional header, consisting of die bars provided with die elements, a collapsible unit for rigidly supporting the die bars during the deforming operation comprising a pair of oppositely-inclined wedges interposed between said die bars, a lever at the upper end of the mandrel arranged to bear on one of said wedges, and links for connecting said lever to the other wedge.

8. A mandrel for internally supporting a tube that is being deformed to produce a sectional header, consisting of die bars provided with die elements, a collapsible unit for rigidly supporting said die bars during the deforming operation composed of a pair of oppositely-inclined wedges interposed between said die bars, means at the lower end of the mandrel for clamping said wedges together, a removable means at the upper end of the mandrel for connecting said wedges with said die bars and for preventing relative longitudinal movement of said wedges, and a device that is adapted to be operated at the completion of the deforming operation to effect a change in the relative position of said wedges so as to permit the die bars to move inwardly towards the longitudinal axis of the mandrel.

JOHN H. HINMAN.
